(57) **CLAIM**

The ornamental design for a compact electronic lock, as shown and described.

DESCRIPTION

FIG. 1 is a front, top, right side perspective view of an interior component of a compact electronic lock showing our new design;

FIG. 2 is a front elevational view of the interior component; FIG. 3 is a right side elevational view of the interior component;

FIG. 4 is a left side elevational view of the interior component;

FIG. 5 is a top plan view of the interior component; FIG. 6 is a bottom plan view of the interior component; FIG. 7 is a back elevational view of the interior component; FIG. 8 is a front, top, right side perspective view of an exterior component of the compact electronic lock showing our new design;

FIG. 9 is a front elevational view of the exterior component; FIG. 10 is a left side elevational view of the exterior component;

FIG. 11 is a right side elevational view of the exterior component;

FIG. 12 is a top plan view of the exterior component; FIG. 13 is a bottom plan view of the exterior component; FIG. 14 is a back elevational view of the exterior component; and,

FIG. 15 is an exploded assembly side perspective view of the compact electronic lock showing both the interior and exterior components.

The broken lines in the drawing figures depict unclaimed subject matter that forms no part of the claimed design.
